ACTUATING MECHANISM FOR WARNING SIGNALS

Alexis F. Gillet, Omaha, Nebr., assignor to E. A. Laboratories, Inc., Brooklyn, N. Y., a corporation of New York

Application February 4, 1935, Serial No. 4,907

5 Claims. (Cl. 116—138)

This invention relates to actuating means for warning signals for use for example with and attachment to a vehicle of internal combustion engine type, more particularly an engine having an intake manifold and provided with a valve operable from the driver's seat for regulating the amount of fuel admitted to the engine for governing the speed and power thereof.

An important object of the invention is to provide a warning signal for the herein stated purposes having actuating means therefor, the parts of which are so constructed and arranged that an open, unobstructed passageway and communication is provided and maintained at all times, during operation, as well as when the mechanism is at rest from the exterior atmosphere through the signal with the connections positioned between it and a source of suction for the actuating thereof, whereby the application of minute degree of suction to said passageway incident to the opening of the speed valve of the engine will cause said means to become instantaneously actuated without the necessity of closing the speed valve partially or wholly, as heretofore practiced.

With the foregoing and other objects in view, the invention will be more fully described hereinafter and will be more particularly pointed out in the claims appended hereto.

In the drawings, wherein like symbols refer to like or corresponding parts throughout the several views:

Figure 1 is a vertical section of a warning signal embodying the present invention and showing the relative position of the parts when the mechanism is at rest.

Figure 2 is a transverse section thereof taken on line 2—2 of Figure 1.

Figure 3 is a plan view of the diaphragm.

Figure 4 is a bottom plan view of the plunger.

Figure 5 is a vertical section of a fragment of the signal and showing the relative position of the plunger and diaphragm during a cycle of operation.

Figure 6 is a plan view of the air passageway-device.

Figure 7 is a vertical section of a fragment of the signal and showing an alternative form of the passageway-device illustrated in Figure 6.

Figure 8 is a bottom plan view taken along the lines 8—8 of Fig. 7.

Figure 9 is a view similar to Figure 7 and showing a further form of said passageway-device.

Figure 10 is a top plan taken substantially on line 10—10 of Fig. 9.

Figure 11 is a view similar to Figure 10 and

showing a still further unit form of the passageway-device shown in Figure 6, the view being taken substantially on line 11—11 of Figure 12.

Figure 12 is a sectional view similar to Figure 9 and showing the unit illustrated in Figure 11. 5

Figure 13 is a view taken substantially on line 13—13 of Figure 14 and showing another form of the passageway-device.

Figure 14 is a vertical section of a fragment of a signal embodying the form of the passageway-device shown in Figure 13. 10

It is well known in the art that, as heretofore practiced, at times when the throttle valve of an engine is opened appreciably for a high speed thereof, or at times when the engine labors such as during the climbing of a hill, that an inadequate or inefficient degree of suction is obtained for application to windshield wiper mechanisms and warning signals of the general class of the present invention. The minimum degree of suction thus provided often is insufficient to cause the spring pressed valves of the prior art signals to move away from contact with their seats or diaphragms, whereby said prior signals fail to sound at all or in instances where a signal is produced the same is too belated for an efficient warning of traffic and particularly is this true in instances when said prior signals are attached to the comparatively high speed motors of present day type. Also in instances when a vehicle and the engine thereof are running at a normal or comparatively slow speed and a point of traffic danger is reached, the operator in order to avoid a collision often suddenly opens the throttle for speeding past said danger simultaneously desiring to warn the traffic by actuating his signal which fails to respond incident to the sudden opening of the fuel admission valve or throttle. 25

The present invention provides an arrangement of parts which utilizes the comparatively small 40 degree of suction obtained and applicable to a suction operated warning signal at the time the throttle of the engine is opened for facilitating an initial vibration of its diaphragm for the production of sound and also provides a mechanism 45 which is highly responsive to changes in the adjustment of engine-throttles without impairing a normal operation of the engine by unduly diluting its fuel mixture.

Referring now to the drawings for a more particular description, 20 indicates generally a warning signal which includes a casing comprised of a lower half portion 21 and an upper half portion 22. The lower part 21 of the casing is substantially cup-shaped in cross section, having an out- 50

55

turned flange 23 and in inturned flange 24. A nut 25 facilitates a connection of the warning signal with the intake manifold of an internal combustion engine, it being understood that a suitable cut-off cock, (not shown), is provided for use at times when it is desired not to employ the device for the production of warning sounds.

Between the flanges 23 and 24 a detent shelf 26 is provided for purposes later explained. The upper half portion 22 of the casing includes a flange 27 which is peened over the flange 23 of the lower half portion during the manufacture of the device and subsequent to the placement of certain later described parts therein, said operation being accomplished by die pressing and squeezing the parts together.

A bell or trumpet 28 may be employed for amplifying sounds produced by the warning signal. The outer end of the bell is in communication at all times with the exterior atmosphere and the inner end thereof is in communication with the interior of the casing or housing through an opening 29 formed through the upper half portion 22 of the housing. The bell 28 may be removably secured to the casing by means of a boss 30 and keepers or screws 31.

The nut 25 is provided with a threaded outlet port 32 for securing thereto a connection or communicating conduit 32'. The securing means between the outlet port or nut 25 and the pipe 32' may consist of any suitable parts such as the threaded sleeve, a pack nut carried thereby for locking the flared end of the pipe 32' to said sleeve as shown in Figure 1.

Prior to the peening of the half portions of the housing together a transversely disposed diaphragm 33, and a plunger 34 carried by a resilient spider 35 are placed within the housing and arranged as shown in Figure 1. Also at such time one of the passageway-devices 36 shown in Figs. 6, 7, 8, 13 and 14 are placed within the housing and will remain in the position initially selected incident to die crushing or squeezing the two portions of the casing together as heretofore mentioned. Prior to said squeezing operation shims 37, preferably formed of cardboard, fiber or the like, are first positioned as shown in Figures 1, 5, 7, 9, 12 and 14.

The diaphragm 33 is provided with a suitable number of apertures (preferably four) as shown in Figure 3. The diaphragm 33 sub-divides the casing and provides a chamber 39 at the suction side thereof and a chamber 39' at the air inlet side thereof and it will be understood that communication between the chambers and with the exterior atmosphere is permitted at all times through the aperture 38 of the diaphragm and with the outlet port 32.

A reciprocable means for cooperation with the diaphragm is mounted in the casing, said means being generally indicated at 40, and preferably including the plunger 34 which may be riveted, spot welded or otherwise suitably secured to the spider 35, the latter having a suitable number of arms. The arms are similar and equi-distantly spaced with respect to each other and radially disposed from a common center. As best shown in Figure 1, the outer ends of the arms rest upon the detent-shelf 26 for a resilient bearing 41 and maintaining the alignment of the plunger 34 constant with respect to the diaphragm.

Means are provided for maintaining the passageway through the diaphragm open at all times by means of the passage-way-device 36 or 36-A or 36-B, any of which may be interposed between

the diaphragm and the plunger for preventing a contact between them at all times whereby the plunger is prevented from closing the aperture 38 of the diaphragm.

Referring to Figure 6, the passageway-device 36 is provided with a centrally disposed aperture 42 which is of lesser diameter than the diameter of the plunger 34 and of greater diameter than the areas embraced by the apertures 38, as shown by the dotted and full lines in Figure 2. The annular wall of the aperture 42 of the member 36 is provided with a plurality of notches 43 for the passage of air therethrough at times when the plunger is in contact with the member 36 for providing a free passage of air at all times from the chamber 39', through the apertures 38 of the diaphragm, and the notches 43 of the member 36 at times when it touches the plunger, and past the perimeter of the plunger and into the chamber 39, and thence through the outlet port 32 and the connection 32' to the source of vacuum.

Alternative forms of the passageway-device 36 may be employed. The form 36-A, shown in Figure 8, consists of a thin metal sheet, the perimeter of which is provided with a plurality of large notches 43-A which perform the same function as the heretofore described notches 43 of the member 36.

The form of passageway-device, shown in Figure 13, may be briefly described as a thin strip of metal 36-B extending across the diaphragm for maintaining the aperture or apertures thereof open at all times and preventing contact between the plunger and diaphragm 33.

The means for maintaining the apertures of the diaphragm open at all times may consist of further structures, shown in Figures 9 to 12, inclusive. Referring to Figures 9 and 10, the form therein illustrated consists of providing the plunger with an annular flange 45 disposed at a right angle with respect to the diaphragm 33. The edge of the flange 45 is provided with a plurality of transversely disposed notches 46 which perform the same function as the heretofore mentioned notches 43 of the passageway-device 36 and when this structure is employed the member 36 may be dispensed with. It is believed to be obvious that the annular flange 45, if provided with holes transversely disposed through it, would perform the same function as the notches 46.

The device illustrated in Figures 11 and 12 contemplate providing the periphery of the plunger with a plurality of notches 47 in alignment with the apertures 38 of the diaphragm and when this modification is employed no annular flange 45 need be provided for the plunger. Also it is believed to be obvious that apertures positioned through the plunger in lieu of the notches 47 would function as well as the latter and for the purpose later described herein relative to all of the forms which are generally referred to herein as a passageway-device. Said passageway-device may consist of a detent, (not shown), for preventing the plunger 40 from having too great a movement toward the diaphragm, said detent being secured to the casing or the nut 25 at one of its ends and the other end arranged for limiting the movement of the plunger towards the diaphragm.

A source of suction or engine is generally indicated at 48 provided with an intake manifold 49, the latter having a tap 50 to which is connected a conduit for a communication of suction to the windshield wiper mechanism of the auto-

mobile. The present invention contemplates the removal of said tap and the substitution therefor of a T or two-way branch, with one of which the said windshield wiper mechanism may be in 5 communication and the other thereof for the warning signal of the instant invention. Said tap and also such two-way branch are well known in the art and believed to need no illustration. Also internal combustion engines and their speed 10 regulating valves being well known are similarly believed to need no illustration or particular description herein.

The pipe or conduit 32' establishes a communication between said tap and the mechanism as 15 shown in Figure 1, and between the ends of the conduit 32' a cut-off valve is provided for closing said passageway 32' completely. The cutting valve may be of any type such as the valve for said purpose shown in my prior Patent No. 20 1,869,142, which also explains a means for operating said valve from the driver's seat.

The transverse area of the pipe 32' and the total area of apertures 38 of the diaphragm must 25 be made small so that the admission of air through the warning signal of the present invention is also comparatively small in quantity, whereby the normal operation of the engine is not impaired by weakening the fuel mixture therefor with an undue dilution of air incident 30 to the operation of the device, while at the same time enough suction is provided through the connection or conduit 32' and through the diaphragm sufficient to cause the latter to vibrate for the production of sound.

In operation a comparatively minimum amount 35 of suction applied to the conduit 32' or suction outlet port 32 of the mechanism causes air to become squeezed between the diaphragm and the plunger through the passageway-device of the 40 present invention causing the diaphragm and plunger to move further away from each other, said initial movement of air instantaneously causing an initial vibration of the diaphragm which is highly responsive to the movement of 45 the air sucked therethrough. Said initial vibration of the diaphragm permits a greater quantity of air to move therethrough, the plunger then occupying an extreme position away from the diaphragm as depicted in Figure 5, from which 50 position it then reciprocates for varying the volume or velocity of the air passing through the diaphragm during the vibrations thereof, said vibrations being communicated to the air within the chamber 39' for production of sound and the amplification of said sound in the bell of the 55 horn 28.

Heretofore when a spring urged valve head was employed, in lieu of the plunger 40, said head making firm contact against its seat or diaphragm 60 a comparatively maximum amount of suction was required to spread the diaphragm away from the valve seat for producing an initial vibration of the diaphragm and as heretofore explained under certain operating conditions of the engine 65 the suction operated warning devices of the prior art fail to operate.

Among other advantages of the present invention it may be mentioned that heretofore operators of motor vehicles have provided the latter 70 with two horns, one electrically actuated, which is used in times of emergency, and a pleasant toned suction operated horn. By means of the

present invention the electrically actuated horns and the excruciating noise thereof may be dispensed with, also the vacuum storage tanks as heretofore used in connection with suction horns are eliminated.

It is obvious that various changes and modifications may be made in the details of construction and design of the above specifically described embodiment of this invention without departing from the spirit thereof, such changes and 10 modifications being restricted only by the scope of the claims.

What is claimed is:—

1. A warning signal comprising a casing having 15 an outlet port to be connected to a source of suction and a port for the intake of actuating air, a vibratory diaphragm in the casing provided with an opening for the passage of air between said ports for vibration of the diaphragm, means disposed within the casing and movable with respect to said diaphragm for varying the volume of air passing therethrough, and means in the casing for constantly assuring the maintenance of an open passageway for air therethrough.

2. A warning signal adapted for connection 25 with a source of suction and comprising in combination, a casing, an apertured vibratory diaphragm dividing the interior of the casing into two chambers of which one is an air admission chamber and the other is a suction chamber, a 30 resiliently mounted plunger in the casing for co-operation with the diaphragm and arranged for varying the movement of air from the air admission chamber to the suction chamber, and through said aperture and means within the casing and 35 acting constantly to prevent the aperture of the diaphragm from becoming completely closed by said plunger.

3. A warning signal including a casing formed 40 with inlet and outlet openings, a vibratory diaphragm extending across said casing and formed with a fluid opening, a valve including a body arranged in line with said latter opening, means for supporting said valve and diaphragm whereby the same may move with respect to each 45 other, and means positioned between said body and diaphragm for constantly maintaining said valve body out of engagement with said diaphragm whereby said diaphragm opening will, under no conditions, be closed by said valve body. 50

4. A warning signal including a casing formed 55 with inlet and outlet openings, a vibratory diaphragm extending across said casing and formed with a fluid opening, a valve including a body arranged in line with said latter opening, means for supporting said valve and diaphragm whereby the same may move with respect to each other, and means overlying said diaphragm body and engageable by the valve to constantly prevent the latter from completely closing said diaphragm opening.

5. A warning signal including a casing formed 65 with inlet and outlet openings, a vibratory diaphragm extending across said casing and formed with a fluid opening, a valve including a body arranged in line with said latter opening, means whereby said valve and diaphragm may move with respect to each other, and said valve body being formed with openings for the passage of fluid whereby, under all conditions, fluid may 70 flow through said diaphragm opening.

ALEXIS F. GILLET.
